DESIGN FOR A CAKE

Louise Pache, Calvert, Kans.

Application March 13, 1945, Serial No. 118,451

Term of patent 7 years

(Cl. D8—1)

To all whom it may concern:

Be it known that I, Louise Pache, a citizen of the United States, residing at Calvert, in the county of Norton and State of Kansas, have invented a new, original, and ornamental Design for a Cake, of which the following is a specification, reference being had to the accompanying drawing, forming a part thereof.

I claim:

The ornamental design for a cake, as shown.

LOUISE PACHE.
